LOCK UNIT

Edward Joseph Williamson, Vancouver, British Columbia, Canada

Application June 18, 1937, Serial No. 148,989

3 Claims. (Cl. 292—340)

This invention relates to a lock unit adapted to hold doors closed under pressure such, for example, as refrigerator, sound-proof and water-tight doors.

5 An object of the present invention is the provision of a lock unit adapted to hold the door closed constantly under pressure.

Another object is the provision of a lock unit adapted to hold a door closed under relatively 10 great pressure with very little leverage.

A further object is the provision of a lock unit adapted to hold a door closed under pressure and having means for regulating the pressure.

15 A further object is the provision of a lock unit which may be operated silently.

A still further object is the provision of a lock unit concealed in the door adapted to hold said door closed under pressure.

20 Yet another object is the provision of a lock unit of very great strength which may be easily operated.

25 There are many locks now in use for holding doors closed but these do not apply pressure to the door in order to ensure a tight fit. There are latches adapted to act against a stationary sloping surface in order to force a door closed but the latch tends to ride back along the sloping surface and release the pressure. At the same time, as the metal wears away, the pressure on the 30 door is lessened.

35 This invention overcomes these disadvantages by providing a lock unit by means of which pressure is constantly applied to the bolt of the door in order to ensure a tight fit at all times. The present lock unit includes means for regulating the pressure on the door to meet various needs and to compensate for any wearing of the various parts.

40 The present invention consists essentially of a lock casing mounted in a door and a keeper mechanism comprising a strike casing mounted in the door frame or in the wall in which the door is located. The strike casing is provided with a ramp or strike plate pivotally mounted therein, means for applying pressure to the free end of the strike plate and means for regulating the pressure of the pressure-applying means. The lock casing is provided with a bolt having means for moving it into and out of engagement 45 with the ramp or strike plate when the door is closed, said casing including means for noiselessly limiting the movement of the bolt as more fully described in the following specification and illustrated in the accompanying drawing, in which,

Figure 1 is a side elevation of the lock unit with its covers removed,

Figure 2 is a horizontal section taken on the line 2—2 of Figure 1 with the bolt entering the strike casing,

Figure 3 is a view similar to Figure 2 with the bolt in locked position, and

Figure 4 is an enlarged horizontal section taken through the strike casing on the line 2—2 of Figure 1.

Referring more particularly to the drawing, 10 is a lock casing having a removable cover 11, a bottom 12 and an end plate 13 by means of which the casing is mounted in a door 14 by screws or the like. A bolt 15 resting on the bottom 12 of the casing, is slidably mounted therein and extends outwardly through an opening 16 in the end plate 13. The bolt 15 is formed at its inner end with a rack 17 and at its outer end with a recess 18 in which a roller 20 is mounted by means of a pin 21. A pinion 22 adapted to mesh with the rack 17, is formed to receive a square shaft 23 extending transversely of the casing 10. The shaft 23 extends through the door 14 and has a handle 24 fixedly mounted on its outer end. 15 A pair of stops 25 and 26 mounted in the casing 10, act as guides for the bolt 15 and are provided with inserts 27 and 28 formed of rubber or other relatively soft, resilient material. A pin 30 is mounted on the upper edge of the bolt 15 and 20 extends upwardly between the stops 25 and 26 so that said stops limits the movement of the bolt. If desired, a lock could be placed in the casing 10 in the space above the pin 30 by means of 25 which the bolt could be locked in its outward position.

The keeper mechanism comprises a strike casing 31 adapted to be mounted in a door frame or wall 32 in which the door 14 is located, said casing having a removable cover 33 and an end plate 34 with an enlarged opening 35 therein. The strike casing 31 is formed with a pair of wedge-shaped blocks 36 and 37 at its top and bottom. The wedge-shaped blocks 36 and 37 are situated with their bases 38 at the inner end of the casing 31 and their apexes 40 terminating adjacent the opening 35 of the end plate 34. A plate 41 having arms 42 and 43, is mounted on the sloping surfaces of the blocks 36 and 37 by screws or the like 44. A strip of rubber 45 of approximately 40 the same width as the arms 42 and 43 is placed between each of said arms and the blocks 36 and 37. The arms 42 and 43 are slightly wider than the blocks 36 and 37 and form an enlarged recess 46 in the plate 41. A ramp or strike plate 47 45

is formed with lugs 48 and 50 projecting outwardly from each side thereof adjacent its outer end. The ramp 47 lies between the blocks 36 and 37 and beneath the plate 41 and its arms 42 and 43 with the lugs 48 and 50 extending into recesses 51 and 52 in the blocks 36 and 37 respectively. The ramp 47 is normally held against the rubber strips 45 under the arms 42 and 43 by springs 53 and 54. These springs are fixedly mounted on a shaft 55 journaled in the top and bottom of the strike casing 31 adjacent the inner end thereof. The springs 53 and 54 are wound around the shaft 55 in a manner similar to a watch spring and are formed with arms 56 and 57 at their outer ends which bear against the under side of the ramp 47 at each side thereof adjacent its inner or free end. The shaft 55 may be turned in either direction to tighten or loosen the springs 53 and 54 in order to increase or decrease the pressure on the ramp 47 and set screws 58 are provided by means of which the shaft is held in the desired position. As stated above, the strike plate 47 is normally held against the underside of the arms 42 and 43 by the springs 53 and 54. The strike plate, however, may be displaced or pivoted on the lugs 48 and 50 at its outer end away from the arms 42 and 43 against the tension of the springs 53 and 54.

In use, the bolt 15 is moved to its innermost position until the door is closed and then the handle 24 is turned thus turning the pinion 22 which, due to its engagement with the rack 11, moves the bolt 15 outwardly. As this bolt moves outwardly, its outer end and the roller 20 enters the strike casing 31 of the keeper mechanism through the opening 35. As the bolt progresses in this direction, the roller 20 engages the ramp or strike plate 47 and pivots it back or displaces it against the tension of the springs 53 and 54 until the bolt reaches its outermost position, as illustrated in Figure 3. The inward and outward movement of the bolt is limited by the pin 30 and the stops 25 and 26. The rubber inserts 27 and 28 make the limiting of the bolt movement noiseless. When it is desired to open the door, the handle 24 is again turned to withdraw the bolt from the strike casing. As the bolt moves out of the strike casing, the springs 53 and 54 move the strike plate 47 back to its normal position against the undersides of the arms 42 and 43, the strips of rubber 45 preventing the strike plate from making a noise when it contacts said arms.

When the bolt is in locked position, the ramp bears against the roller 20 under the pressure of the springs 53 and 54. In this way, pressure is directly applied to the bolt in order to force the door firmly closed. The pressure is in the direction of the closing movement of the door so that there is no tendency for the bolt to move back into the lock casing 10 under this pressure. If it is desired to increase the pressure on the door or to compensate for the wearing of any of the various elements of the lock unit, it is only necessary to loosen the set screws 58 and turn the shaft 55 to tighten the springs 53 and 54.

From the above it will readily be seen that a

lock unit which may be operated noiselessly has been provided by means of which a door may be held tightly closed under constant pressure and including means for regulating said pressure.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. A keeper mechanism comprising a strike casing adapted to receive a bolt slidably mounted on a door when the latter is closed, a plate mounted in said casing lying angularly across the path of the bolt, said plate having a recess formed therein, a strike plate pivotally mounted at its outer end in the casing lying beneath the plate and overlapping the recess therein, and spring means adjacent the inner end of the strike plate for normally holding said strike plate against the bottom of the angularly disposed plate, said strike plate being adapted to be displaced against the tension of the spring means by the bolt as it is moved into the strike casing whereby pressure is applied to the bolt in order constantly to hold the door closed under pressure.

2. A keeper mechanism comprising a strike casing adapted to receive a bolt slidably mounted on a door when the latter is closed, a plate mounted in said casing lying angularly across the path of the bolt, said plate having an enlarged recess formed therein, a strike plate pivotally mounted in the casing lying beneath the plate and overlapping the recess therein, springs mounted in the casing having arms bearing against the strike plate adjacent its free end, said strike plate being adapted to be displaced against the tension of the springs by the bolt as it is moved into the strike casing whereby pressure is applied to the bolt in order constantly to hold the door closed under pressure, and means for tightening and loosening the springs to regulate the pressure on the strike plate.

3. A keeper mechanism comprising a strike casing adapted to receive a bolt slidably mounted on a door when the latter is closed, wedge-shaped blocks mounted in the casing at its top and bottom, a plate having arms mounted on the sloping surfaces of the blocks, said arms being wider than the blocks, a strike plate pivotally mounted between the blocks, lugs formed at the outer end of the plate extending into recesses in the blocks, springs mounted in the strike casing having arms bearing against the strike plate adjacent its inner end normally to hold the plate against the underside of the arms, said strike plate being adapted to be displaced against the tension of the springs by the bolt as it is moved into the strike casing whereby pressure is applied to the bolt constantly to hold the door closed under pressure and means for tightening and loosening the springs to regulate the pressure on the strike plate.

EDWARD JOSEPH WILLIAMSON.
